UNITED STATES PATENT OFFICE.

DAVID S. BACHELDER, OF TILDEN, ILLINOIS, ASSIGNOR OF ONE-HALF TO JAMES CONNOR, OF TILDEN, ILLINOIS.

COAL-DRILL.

1,251,323.

Specification of Letters Patent. Patented Dec. 25, 1917.

Application filed April 19, 1916. Serial No. 92,191.

To all whom it may concern:

Be it known that I, DAVID S. BACHELDER, a citizen of the United States, residing at Tilden, in the county of Randolph and State 5 of Illinois, have invented new and useful Improvements in Coal-Drills, of which the following is a specification.

This invention relates to coal drills and it consists in the novel features hereinafter described and claimed.

An object of the invention is to provide a structure especially adapted for drilling coal, the parts and features being so arranged that the chips or bits of coal or rock 15 as they are cut from the bed are quickly removed from the bore which the drill structure opens.

With this object in view the drill comprises a head having at one end a socket by 20 means of which it may be attached to a drill rod in a usual manner, the said head having at its other end portion openings one positioned at the center of the head and adapted to receive the center drill bit and the other 25 openings arranged one at each side of the said central opening and adapted to receive the shank of the side drill bits. The said head is provided at its exterior with spirally disposed spaced ribs the outer edges of 30 which are relatively sharp and the head between the said ribs is curved or concaved thereby eliminating angles and sharp corners which would interfere with the free 35 passage of the drill's dust along the said ribs as the said material is being forced from the bore which is opened by the drill structure. The side drill bits have their outer or forward 40 portions spiral twisted to conform substantially with the spiral disposition or twist of the ribs located at the exterior of the head and the said side drill bits are provided at their forward ends with cutting edges which are substantially radially disposed with relation to the axis of the head.

45 In the accompanying drawing:

Figure 1 is a side elevation of the coal drill;

Fig. 2 is a longitudinal sectional view of the same;

50 Fig. 3 is a similar view cut on a plane at a right angle to that on which the section of Fig. 2 is cut;

Fig. 4 is a transverse sectional view cut on the line 4-4 of Fig. 1;

Fig. 5 is a similar view cut on the line 55 5-5 of Fig. 1.

The coal drill comprises a head 1 having at one end a socket 2 adapted to receive a rod whereby the said head may be rotated in a usual manner. Any suitable means may be provided for securing the head upon the rod in a manner which will permit the head to be removed from the rod when desired.

The head 1 is provided at its forward end with a central non-circular opening 3, the inner end of which communicates with the inner end of the socket 2. A center drill bit 4 is provided with a shank 5 which fits snugly in the opening 3 and a set screw 6 passes transversely through the side of the head 1 and bears at its inner end against the side of the shank 5 and serves as means for detachably holding the bit 4 in the opening 3. The outer or forward end of the bit 4 is pointed as at 7 in a usual manner.

The head 1 is provided at its end and at the opposite sides of the opening 3 with openings 8 which extend longitudinally of the said head and merge at their inner ends into slots 9 which open at the opposite sides 80 of the head 1. The openings 8 are angular or non-circular in transverse section. Side drill bits 10 are provided with non-circular shanks 11 which fit snugly in the openings 8 and the inner 85 ends of the said shanks 11 are received in the slots 9. The outer portions of the side drill bits 10 are spirally twisted as at 12 and the said bits 10 are provided at their outer or forward ends with cutting edges 13 which 90 are disposed approximately radially with relation to the axis of the head 1 and at acute angles with relation to the said axis. Set screws 14 pass through the head 1 and bear at their inner ends against the shank 95 11 of the side bit 10 and serve as means for detachably holding the shanks in the openings 8.

The head 1 is provided at its exterior with spirally disposed ribs 15 which are spaced 100 from each other. The forward ends of the said ribs 15 terminate at one end of the openings 8 and consequently the said ribs 15 are substantially in spiral alinement with the outer twisted edges of the side bits 10 105 when the said bits are in position in the openings 8. The ribs 15 are relatively sharp at their outer edges and the material

between the said ribs 15 is concaved or curved whereby the head 1 between the said ribs 15 is devoid of sharp corners or angles which would interfere with the passage of material through the space between the adjacent ribs 15.

In operation the center drill bit 4 is positioned against relatively hard material as for instance rock or slate and the head 1 is 10 rotated in the usual manner. The center drill bit 4 penetrates into the said hard material and the chips or dust cut by the bit 4 is taken up by the twisted portions 12 of the side drill bit 10 and moved into the 15 spaces between the ribs 15 which in turn operate upon the said material to work the same toward that end of the head 1 which is connected with the rod which operates the same at the socket 2.

20 In view of the fact that the ribs 15 are sharp at their outer edges and the head 1 between the ribs is devoid of angles or sharp corners there are no spaces in which the fine material may accumulate and interfere with 25 the operation of the drill or the free passage of the chips from the bore which is being cut by the drill.

Following the bit 4 the cutting edges 13 of the side drill bits 10 enter the material 30 and enlarge the bore and the chips which are cut from the solid rock or coal by the cutting edges 13 of the side bits 10 are moved along the twisted portions of the said side bits 10 and pass into the spaces between the 35 ribs 15 which in turn operate upon the said material to move it along the head 1 and eject it from the head at the ends thereof which is provided with the socket 2.

When it is desired to sharpen the bits 4 40 and 10 or to renew the same the set screw 6 is removed from the head 10 whereby the bit 4 may be slipped out of the opening 3 and the set screws 14 are removed from against the shank 11 whereby the bits 10 45 may be removed from the openings 8. In the event that the shanks 11 stick in the openings 8 an implement may be inserted through the slots 9 and against the inner ends of the said shanks for forcing the 50 shanks out of the openings 8.

With the drill, such as described herein, it is found the coal and balls of sulfur lodged therein are cut very rapidly and evenly and the speed at which the hole is formed 55 correspondingly increased. At the same time, it is found that the drill turns very lightly and

may be employed in unskilled hands now in common use in many coal mining districts. The specific arrangement and disposition of the exterior surfaces of the head is particularly advantageous in that they facilitate the removal of particles of dust from the hole and thereby prevent interference to the proper operation of the drill from this cause. Furthermore the material of which the head 60 is composed is so disposed about the openings 8 that the presence of the said openings does not weaken the head hence they may be extended for a considerable distance in the head and in view of the fact that they are 65 comparatively long, they may retain drill bits having long shanks. These bits having long shanks are susceptible of being sharpened many times before their shanks are rendered too short to be securely held in the 70 openings. The sharpening of the bits is effected by flattening portions of their shanks on the horn of an anvil, and peening down their cutting edges with a hammer. Hence the bits may be kept in proper condition 75 without the use of special or expensive sharpening machines or devices.

From the foregoing description taken in conjunction with the accompanying drawing it will be seen that a coal drill of simple 80 and durable structure is provided and that the same will efficiently operate to open a bore in solid coal or rock and remove the chips or cut material from the said bore promptly during the operation of forming 90 the bore in the said solid material.

Having described the invention what is claimed is:

A drill comprising a head provided with openings which extend longitudinally of the 95 head at the opposite sides of the axis of the head and parallel therewith and adapted to receive drill bits, said openings at their inner ends terminating in slots which open at the sides of the head, spaced ribs acuminate in 100 transverse section and spirally disposed along the periphery of the head at the opposite edges of the slots, the surfaces of the material of the head between the ribs being concavely curved longitudinally of the 105 head and convexely curved transversely thereof from edge to edge of the adjacent ribs and the said surfaces intersecting each other at the keen edges of the ribs.

In testimony whereof I affix my signature. 110

DAVID S. BACHELDER.
